UNITED STATES PATENT OFFICE

172,446

FIELD LATRINE UNIT

Frederick T. Sheffield, Alexandria, Va., assignor
to Wm. H. Singleton Co., Inc., Arlington, Va.,
a corporation of Virginia

Application September 5, 1952, Serial No. 21,345

Term of patent 14 years

(Cl. D4—4)

To all whom it may concern:

Be it known, that I, Frederick T. Sheffield, a citizen of the United States of America, residing at Alexandria, in the State of Virginia, have invented a new, original, and ornamental Design for Field Latrine Unit, of which the following is a specification, reference being had to the accompanying drawing forming part thereof.

In the drawing:

Fig. 1 is a perspective view of a field latrine unit embodying my new design, as seen from one side thereof;

Fig. 2 is a perspective view of my field latrine unit as seen from the opposite side of the same.

I claim:

The ornamental design for a field latrine unit, as shown.
